UNITED STATES PATENT OFFICE

170,037

AIRPLANE

Carroll Williams, Gladwyne, Pa.

Application March 21, 1952, Serial No. 18,988

Term of patent 14 years

(Cl. D71—1)

To all whom it may concern:

Be it known, that I, Carroll Williams, a citizen of the United States, residing at Gladwyne, in the county of Montgomery and State of Pennsylvania, have invented a new, original, and ornamental Design for an Airplane, of which the following is a specification, reference being had to the accompanying drawings, forming a part thereof.

Figure 1 is a top plan view of an airplane, showing my new design;

Figure 2 is a side elevational view;

Figure 3 is a front elevational view;

Figure 4 is a rear elevational view.

The dominant features of my design reside in those portions shown by means of full lines.

I claim:

The ornamental design for an airplane, as shown and described.

CARROLL WILLIAMS.
